OLIVIER LAROCHE, OF HAMILTON, ONTARIO, CANADA, ASSIGNOR TO CANADIAN KNITTING COMPANY LIMITED, OF HAMILTON, ONTARIO, CANADA, A CORPORATION OF CANADA.

STOP-MOTION FOR KNITTING-MACHINES.

1,212,367.

Specification of Letters Patent. Patented Jan. 16, 1917.

Continuation in part of application Serial No. 727,311, filed October 23, 1912. This application filed January 12, 1914. Serial No. 811,691.

To all whom it may concern:

Be it known that I, OLIVIER LAROCHE, a subject of the King of Great Britain, residing at Hamilton, in the county of Wentworth and Province of Ontario, Canada, have invented certain new and useful Improvements in Stop-Motions for Knitting-Machines, of which the following is a full, clear, concise, and exact description, reference being had to the accompanying drawings, forming a part of this specification.

My invention pertains to stop-motions for knitting machines, *i. e.*, to devices for arresting the operation of a knitting machine in the event of a yarn thread breaking, or in case of the occurrence of a knot in a yarn thread, or in case of a yarn thread being placed under an undue tension.

The invention is particularly directed to stop-motions for use in connection with knitting machines of the spring-needle type. In the operation of knitting machines of the spring-needle type, the quality of the work produced is marred, and sometimes the work 25 is completely spoiled, if one or more of the yarn threads is delivered to the machine at an unduly high tension.

It is one of the objects of my invention, therefore, to produce a stop-motion in the use of which the yarn thread is permitted to enter the machine at a tension which is not appreciably higher than if no stop-motion were employed.

Further, in the use of knitting machines 35 of the spring-needle type, the yarn threads are taken by the machine at an exceedingly high rate of speed, so that the end of a broken yarn thread will reach the machine very quickly. If a broken end reaches the 40 machine during the running of the latter, a "press-off" occurs, and a quantity of material is wasted.

It is another object of my invention, therefore, to provide a stop-motion which 45 will operate with extreme rapidity, thereby to insure that the operation of the machine be arrested before the end of a broken thread can reach the machine.

It is another object of my invention to 50 produce a stop-motion which will at all times be certain in its operation, which will be convenient in use and easy to re-set after

having been actuated, and which will be of a durable construction and not liable to get out of order in the course of use.

It is still another object of my invention to improve upon stop-motions for knitting machines generally.

The present application is in part a continuation of an application filed by me October 23, 1912, Serial No. 727,311.

By way of example, I have described in the following specification and shown in the accompanying drawings one form of stop-motion embodying my invention as applied to a knitting machine of the spring-needle type. I wish it understood, however, that the invention may be embodied and employed in other manners than that which I have described and shown, and that changes may be made in the details of construction of the embodiment which I have described and shown without exceeding the scope of my invention as defined in the appended claims.

In the drawings: Figure 1 is a plan showing the needle-supporting cylinder and some of the associated parts of a knitting machine of the spring-needle type intended for the production of a tubular knitted fabric, 80 having a stop-motion constructed in accordance with my invention applied thereto; Fig. 2 is an end view showing one of the thread-engaging units; Fig. 3 is a front view of the same; Fig. 4 is a fragmentary plan of the clutch-trip; Fig. 5 is a plan showing the clutch-trip-actuating latch; Fig. 6 is an end view of the same; Figs. 7 and 8 are an end view and a plan, respectively, of the brake mechanism; Fig. 9 is an 90 end view of the brake-actuating latch; Fig. 10 is a plan of the same; Fig. 11 is a perspective view of a portion of one of the thread-engaging units; Fig. 12 is a section on the line 12-12 of Fig. 11, looking in the 95 direction of the arrows; Fig. 13 is a plan of the shears; Fig. 14 is a section on the line 14-14 of Fig. 11, looking in the direction of the arrows; and Figs. 15 and 16 are a plan and an end view, respectively, of portions of the actuating shaft and the trip shaft, showing the springs for holding the latter in operative position.

The same reference characters refer to

the same parts throughout the following specification and the several figures of the accompanying drawings.

Referring now particularly to Fig. 1, this figure shows a machine of the spring-needle type intended for the production of a tubular knitted fabric, such as is used, for instance, in the manufacture of underwear. This machine is of a construction well known in the art, and includes a needle-supporting cylinder 20, upon which the needles 21 are mounted. A number of yarn threads 22 may be used simultaneously in the machine (four of such threads being shown in the drawing), each yarn thread being mounted on a bobbin 23 and being delivered to a guide 24, through which it is fed, by a stitch wheel 25, to the needles 21. The guide 24 and stitch wheel 25, together with associated mechanism constitute a stitching unit, one of which is provided for each of the yarn threads used in the machine. These stitching units are disposed equidistantly around the needle cylinder 20; but for the purposes of this specification it has only been necessary to show a portion of one of them. An overhead take-up (not shown) driven by a vertical shaft 26, receives the work as it is delivered upward in cylindrical form, from the needles. Machines of this character are usually equipped with a stop-motion which throw off the drive whenever there is a "press-off", i. e., whenever, by reason of some failure of the mechanism to operate properly or by reason of a broken thread, the work leaves the needles and thus the continuity of the piece is broken. One of the most usual causes of a "press-off" is a broken thread.

40 A stop-motion of a well known kind is shown in Figs. 1 and 4: It includes a feeler having a pivoted finger 27, which rests upon the work near the needles, during the revolution of the same. A spring 28, acting upon the stem 29 which supports the finger 27, holds the finger against the work. The tendency of this spring is to rock the stem in a direction toward the work; but normally, by reason of the engagement of the finger with the work, this rocking of the stem is prevented. In case, however, a hole in the work should occur, the finger 27, would enter such hole, and the stem 29 would be rocked under the action of the spring 28. The same result would occur if there should be a "press-off", since the support for the finger would be removed in this case also.

When the stem 29 is rocked, as described above, a pin 30 thereon strikes one end of a pivoted dog 31, the other end of which is formed with a hook 32 which normally retains the end of a clutch-throwing lever 33. By striking the dog 31, the pin 30 causes the hook 32 of the latter to release the lever

33, whereupon the clutch is thrown out and the machine stopped. The mechanism thus far described is of a character well known in the art and consequently does not need further description.

The mechanism now to be described trips the dog 31, thereby throwing out the clutch, whenever a yarn thread breaks, whenever a cop becomes exhausted, whenever a yarn thread is under an undue tension, and whenever a knot occurs in one of the yarn threads. Simultaneously with the tripping of the dog 31, the mechanism applies a brake to the cylinder 20, thereby effecting an instant stoppage of the machine. The mechanism is supported upon end standards 34 which are connected longitudinally by a metallic shelf 36. The standards 34 rise from the bobbin supporting back table 37, with which the machine is provided, the bobbins being positioned side by side beneath and somewhat to the front of, the shelf 36. A horizontal trip-shaft 38 is rockably mounted in brackets 39 carried by the shelf 36. This shaft carries (Figs. 5 and 6) an upwardly bent hook 40, which normally engages the rear side of a clutch-trip-actuating latch 41 which is pivoted upon a bracket 42 extending forwardly from the shelf 36. A retractile spring 43 holds the latch 41 in engagement with the hook 40; and when the hook is removed from the path of the latch 41 by reason of the shaft 38 being rocked, the latch will snap rearward under the action of the spring. The latch 41 is connected, by means of a wire or the like, 44, with the rear end of the pivoted dog 31 above referred to (Fig. 4); so that, when the latch is pulled over by its spring, the dog 31 will be rocked about its pivot, whereupon the clutch-throwing lever 33 will be released and the clutch thrown out. It will be seen from the above that the drive is thrown off, through the agency of the clutch-trip-actuating latch 41, whenever the trip-shaft 38 is rocked.

In addition to the hook 40, the trip-shaft 38 is provided with a pin 50 (Figs. 7-10) which engages the front side of a brake-actuating latch 51 in the shape of a bell-crank lever. The latch 51 is pivoted upon a bracket 52 carried by the shelf 36, and is held against the pin 50 by means of a spring 53. The front end of the latch 51 is provided with a retaining hook 54 which normally engages in front of the top end of a pivoted brake-tripping lever 55, thus securing the latter against movement. The bracket 52 is formed with a guide slot 56 for receiving the top end of the lever and maintaining it in operative relation with the hook 54, this slot being flared outwardly at its front end to facilitate the returning of the lever 55 to its original position after it has been released in the manner described

below. A spring 58 holds the lever 55 against the latch 51. When the latch is released, this spring causes the lever 55 to snap forward. The lever 55, by its forward movement, operates a brake 59, which is connected with the lever through a link 60. Normally, as has been said, the hook 54 holds the lever 55 in its rearward position, with the brake off; but when the trip-shaft 38 is rocked (thus causing the pin 50 to rock the latch 51 so that its hook 54 is moved out of the path of the lever 55), the lever 55 is permitted to spring forward, thereby causing the brake 59 to be thrown on. Thus the rocking of the trip-shaft 38 not only results in the throwing out of the clutch, as described above, but it also effects the application of the brake. The result of the trip-shaft 38 being rocked, is, therefore, that the machine is immediately stopped. By mechanism now to be described, the trip-shaft 38 is caused to rock whenever a yarn thread breaks or a cop becomes exhausted, whenever one of the yarn threads is placed under a too great tension, and whenever a knot occurs in a yarn thread. This mechanism includes a plurality of thread-engaging units, one of which is provided for each of the yarn threads used in the machine. These units may be of identical construction; and a description of one of them, therefore, will suffice. Each of the units includes a bracket 61 (Figs. 2, 3, 11 and 12) extending frontwardly from the shelf 36, and having its front end bent down so as to provide a vertical portion 62. The lower end of the bracket 62 is formed with a thread-receiving notch 63, the upper part of which is beveled so as to facilitate the passage of the thread therethrough. Secured to the rear of the bracket portion 62 is a guide wire 63^a, which extends forward beneath the notch 63 and in connection with the notch forms a thread guide having an opening in its side through which the thread may be passed in threading the guide. A second guide, 64, extends forward from the shelf 36, below the guide 63^a, and serves to maintain the thread in position between the blades of the shears and also serves to arrest knots or tangles in the thread. Above the thread guide 63, 63^a, the bracket portion 62 is provided, at the front thereof, with a thread guide 65 also having an open side to facilitate its threading. In the use of the mechanism, the thread 22 passes from the bobbin to the knot-arresting guides 64, between the shear blades, through the guides 63, 63^a and 65, and thence vertically upward over a hook 66 (to be described below) and thence to the feed guide 24 and stitch wheel 25. Each unit is provided with a horizontally disposed controller arm 67 which is arranged to pass laterally across the face of the guide 63, 63^a in position to be supported by the thread passing therethrough. This arrangement enables the controller arm to be supported without offering any appreciable resistance to the travel of the thread and without, therefore, appreciably increasing the tension thereon. The arm 67 is preferably made of fine wire, and is mounted on a pin 68 projecting from the collar 69. The collar 69 is rockably mounted on a stem 70 which projects forward from the under side of the shelf 36. The controller arm 67 is very light and the weight of the parts connected therewith is so distributed that the arm will rest lightly on and be supported by the thread so long as the thread remains unbroken (Fig. 11). In case, however, the thread should break, or be severed in the manner to be hereinafter described, or in case the cop should become exhausted, the end of the controlling arm, being deprived of its support, would drop, the collar 69 rocking in a contra-clockwise direction on the stem 70. The rocking movement of the collar 69 which thus results from the dropping of the end of the controlling arm owing to the breaking of a thread, effects a temporary coupling of the trip-shaft 38 with an actuating shaft 73, which is mounted in the brackets 39 immediately to the rear of the trip-shaft. The actuating shaft is continuously rotated in the direction of the arrow (Fig. 11), by means of a belt 74 deriving power from the take-up shaft 26 (Figs. 1, 5 and 6). The actuating shaft 73 is provided with a plurality of star-wheels 72, one of which cooperates with each of the thread-engaging units. Besides the pin 68, the collar 69 is provided with a second pin 71, which, when the collar rocks as described above, falls between the teeth of the coöperating star-wheel 72 and onto a pin 75 which projects rearwardly from the trip-shaft 38 immediately beneath the pin 71 of each thread-engaging unit, the pins 75 being located out of the planes of the star-wheels 72. As has been said, the actuating shaft 73 rotates continuously in the direction of the arrow so long as the knitting machine is running. When, therefore, by reason of the controlling arm 67 having dropped, the pin 71 falls between the teeth of the star-wheel 72 and onto the pin 75, the tooth immediately above the pin 71 will, during the rotation of the star-wheel, press this pin downward upon the pin 75 of the trip-shaft, thus causing the trip-shaft to quickly rock in its bearings, against the action of a spring 38^a (Figs. 15 and 16). The result is that the latches 41 and 51 are immediately actuated to effect the throwing out of the clutch and the application of the brake, respectively, as described above. The mechanism so far described, therefore,

quickly stops the machine whenever, by reason of the severance or failure of the thread, the controlling arm 67 drops.

Besides stopping the machine when a yarn thread breaks, the mechanism also stops it when an undue tension upon one of the yarn threads occurs. It does this by cutting the thread and thus causing the controlling arm to drop. To this end a pair of shears are provided, consisting of a fixed blade 77 (Figs. 11, 13 and 14), carried by a rod 78 suspended from the bracket 61, and a movable blade 79 rockably mounted on the rod 78. A spring washer or the like 80 bears upon the movable blade 79 and holds it in cutting engagement with the fixed blade 77. The shears are disposed so that the thread 22 passes directly between the blades thereof on its way from the knot arresting guide 64 to the guide 63, 63^a; so that, when the shears are operated, the thread will be cut above the knot, thus leaving the severed thread free to be drawn toward the needles.

The movable shears blade 79 has an inclined cam slot 81 formed therein, which receives the correspondingly inclined flattened end 82 of an actuating arm 83. The actuating arm 83 is pivoted, at 84, to one side of the bracket-portion 62 (Figs. 2, 3 and 11).

The arm 83 is beveled at its upper end and engages in a loop which is formed in a detent member 85, the member 85 being pivoted, at 86, to a post 87 which extends vertically upward from the bracket 61. The post 87 is provided with an extension 88, at the upper end of which is pivoted, at 89, an upright 90 having at its top end the hook 66 above referred to. The pivoted upright 90 is formed with a downwardly extending foot 91 which interlocks with the top end of the detent member 85, so that when the upright 90 is rocked about its pivot, the detent member 85 is likewise rocked. A spring 92 is connected between the pivoted upright 90 and the post 87, which spring tends to hold the upright in normal vertical position. A spring 93 is connected between the actuating arm 83 and an extension 94 projecting forwardly from the bracket portion 62.

With the parts in the position shown, the actuating arm 83 is retained by the detent member 85; and it will remain in this condition so long as the tension of the thread is within the desired limits. In case the tension of the thread should be increased, however, the upright 90 will be rocked forwardly about its pivot, thereby effecting a corresponding rocking of the detent member 85. By the time the tension has increased to such an extent as to become undesirable, the detent member 85 will have been rocked about its pivot sufficiently to release the end of the actuating arm 83, whereupon the latter will snap forward under the action of the spring 93. By reason of the engagement of its end

82 in the cam slot 81 of the shears blade 79, this snapping forward of the actuating arm 83 will cause the shears blade 79 to move across the blade 77, whereby the thread is severed. The severing of the thread effects the stoppage of the machine in the manner described above. It will be seen, therefore, that the stop motion is actuated to stop the machine whenever too great a tension occurs at one of the yarn threads.

If a knot or tangle in one of the threads should occur it will become wedged or arrested at the guide 64, causing an increase in the tension on the thread which will result in the cutting of the thread above the knot 80 and a stopping of the machine before the severed end of the thread has had time to reach the needles. In case a knot should pass through the guide 64 it is possible that such knot might become wedged or arrested at the guide 63, 63^a, so that the controlling arm would not fall after the shears had been operated to cut the thread in the manner above described. In such case the controller arm would not operate to immediately stop the machine upon the cutting of the thread, but the machine would continue running, causing the breakage of the yarn thread at some other point, and the broken end might enter the machine. To prevent any possibility of this, I mount loosely upon the actuating shaft 73 a collar 96 provided with a hook 97 which engages around the actuating arm 83. The collar 96 has formed in the periphery thereof a channel 98 of limited length, which channel receives a pin 99 extending forwardly from the trip shaft 88. When, therefore, the actuating arm 83 snaps forward, it will cause the collar 96 to be rocked upon the shaft 73, by reason of the engagement of the arm 83 with the hook 97. When the collar 96 is thus rocked, the top end of its channel 98 will strike the pin 99 and cause the trip shaft 88 to be rocked sufficiently to release the latches 41 and 51, the machine being thereby stopped.

When the defect which resulted in the actuation of the stop-motion has been remedied and the ends of the thread pieced together, the mechanism will be rethreaded and the parts reset by hand. In order to reset the parts, it will usually be necessary to turn the actuating shaft 73 backward somewhat in its bearings, in order to release the pin 71, which will have been clamped between the pin 75 and a tooth of the star-wheel 72. It will be understood of course that the upright 90 and the spring 92 may be adjusted and arranged so as to operate upon the occurrence of any predetermined degree of tension, to suit the requirements of each particular case.

The actuation of the stop-motion when an undue tension thereon occurs, has several advantages. In the first place, it effects the

stoppage of the machinery before harm can result owing to the increased tension on one of the threads; and thus avoids bad work and saves much material and time which would otherwise be wasted owing to the occurrence of holes, etc., in the work. Again, it insures that the thread shall not break near its point of entry into the machine, and thus, perhaps, cause a press-off. Supposing, for instance, that an undue strain is being placed upon the yarn thread, the latter might, except for the mechanism described above, break at any point between the machine and the bobbin; and, if there should be a weak spot in the thread, which spot was at the time near the stitch wheel, the thread would probably break at that spot. In such a case, a press-off would occur. Anything of the kind is avoided by the mechanism described above; since the machine will be stopped immediately upon the occurrence of the undue strain, whereupon the cause of such strain may be removed. Again, the mechanism described above prevents knots, bunches, or other imperfections in the yarn from entering the machine where they would be liable to cause choking of the feed devices and breakage of the thread at its point onto the machine.

The mechanism is simple in construction and certain in its operation. It offers but little resistance to the passage of the yarn thread, since the path traversed by the latter differs only slightly from that which it would follow if no stop-motion were employed. The mechanism does not, therefore, increase appreciably the tension at which the thread operates; and this is a most important advantage. The mechanism operates with extreme rapidity, effecting the stoppage of the machine practically simultaneously with the occurrence of the defect. This is another most important advantage, since it prevents a broken end from reaching the machine even when the latter is running at a high speed.

The mechanism may be used, of course, in connection with other machines than that indicated in the drawings; and changes may be made in the machine for this and other purposes. Such changes in the embodiment of my invention are contemplated by me, what I claim being:

1. A stop-motion for knitting machines comprising a clutch-operating device, a support, a rockable shaft mounted on said support, adapted, when rocked, to actuate said device, an actuating shaft mounted on said support and continuously driven from the machine, a guide mounted on said support adapted for the passage of thread therethrough, a fixed support, a member movably mounted on said support and cooperating with said guide, said member being supported by the thread passing through said guide, and means, associated with said mem-

ber, for interlocking said actuating shaft and said rockable shaft when said member moves, due to the breaking or severing of a thread, whereby said actuating shaft causes said rockable shaft to be rocked, and means operated upon an increase in the tension on the thread to sever the thread between the thread supported member and the thread supply.

2. The combination with a knitting machine, of mechanism for arresting the operation of said machine when the continuity of the yarn thread of the machine is broken, said mechanism including a clutch-operative device, a brake, latching means for actuating said device and said brake, a continuously rotating actuating shaft, having a projection thereon, a rockable shaft having a projection thereon, detent means for said latching means carried by said rockable shaft, a pair of vertically arranged guiding eyes, a movable member located, when in one of its positions, in the path of the projection of said actuating member and in operative relation with the projection of said rockable shaft, means resting upon said thread between said eyes and normally holding said movable member out of the path of the projection of the actuating member, whereby, when the continuity of such yarn thread is broken, said movable member effects a coupling between said rotating shaft and said rockable shaft, to remove said detent means from said latching means.

3. The combination with a knitting machine including a rotary needle-supporting head, of mechanism for arresting the operation of said machine when the continuity of the yarn thread of the machine is broken, said mechanism including a clutch operating device, a releasable brake, adapted, when, released, to bear upon said head, latching means for actuating said device and releasing said brake, a continuously rotating actuating shaft, having a projection thereon, a rockable shaft having a projection thereon, detent means for said latching means carried by said rockable shaft, a movable member located, when in one of its positions, in the path of the projection of said actuating member, and in operative relation with the projection of said rockable shaft, but normally held out of such position by said yarn thread, whereby, when the continuity of such yarn thread is broken, said movable member effects a coupling between said actuating shaft and said rockable shaft, to effect the removal of said detent from said latch.

4. The combination with arresting mechanism, of a rockable shaft, adapted, when rocked, to actuate said mechanism, an actuating shaft, a thread-supported member adapted, when released, to connect said first

and second named shafts, whereby said first named shaft is rocked, a shears, a thread-controlled tension device for actuating said shears, and a device, controlled by said tension device, for rocking said first named shaft.

5. The combination with arresting mechanism, of a latch device adapted, when released, to actuate said mechanism, a rockable shaft adapted, when rocked, to release said latch, an actuating shaft, a thread-supported member adapted, when released, to connect said first and second named shafts, whereby said first named shaft is rocked, a shears, a thread-controlled tension device for actuating said shears, and a device, controlled by said tension device, for rocking said first named shaft.

6. The combination with a clutch throwing device and a brake, of a latch device adapted, when released, to actuate said clutch throwing device, a second latch, adapted, when released, to actuate said brake, a rockable shaft adapted, when rocked, to release both of said latches, an actuating shaft, a thread-supported member adapted, when released, to connect said first and second named shafts, whereby said first named shaft is rocked, a shears, a thread-controlled tension device for actuating said shears, and a device, controlled by said tension device, for rocking said first named shaft.

7. The combination with arresting mechanism, of a rockable shaft adapted, when rocked, to actuate said mechanism, an actuating shaft, a thread-supported member adapted, when released, to connect said first and second named shafts, whereby said first named shaft is rocked, a shears, a spring actuated pivoted arm adapted, when released, to actuate said shears, a thread-controlled detent for said arm, a rockable member having a portion thereof in engagement with said arm and having an abutment thereon, and an abutment on said rockable shaft co-operatively disposed with respect to the abutment of said rockable member, whereby said rockable shaft is rocked upon said arm being released.

8. The combination with an arresting mechanism, of a rockable shaft adapted, when rocked, to actuate said mechanism, an actuating shaft, a thread-supported member adapted, when released, to connect said first and second named shafts, whereby said first named shaft is rocked, a shears, a spring actuated pivoted arm adapted, when released, to actuate said shears, a thread-controlled detent for said arm, a collar loosely mounted on said actuating shaft and having a projection in engagement with said arm, said collar being provided with an abutment, and an abutment on said rockable shaft co-operatively disposed with re-

spect to the abutment on said collar, whereby said rockable shaft is rocked upon said arm being released.

9. In a stop-motion a shears including a fixed blade and a movable blade having a cam slot therein, a pivoted spring actuated arm having one end thereof in engagement with said cam slot, and a thread-controlled detent normally engaging the upper end of said arm.

10. A stop-motion for knitting machines, having, in combination, stopping devices, a rock shaft for rendering said devices active to stop the machine, a rotating actuating shaft parallel to the rock shaft, a series of coupling devices arranged at intervals along the shafts, a thread-supported controller corresponding to each coupling device, the fall of which when the continuity of the thread is broken couples the shafts together, a thread cutter between each controller and the corresponding thread supply, a knot arrester between each cutter and the corresponding thread supply, and a thread-engaged controller for each cutter constructed to be operated by an increased tension on the corresponding thread.

11. A stop-motion for knitting machines, having, in combination, stopping devices, and mechanism for controlling the stopping devices by the thread fed to the machine comprising a knot arresting guide arranged over the thread supply, a thread cutter above the guide, a thread guide above the cutter, a controller arm resting on the thread beyond the guide, a movable thread guide above the controller, said guides being so arranged that the thread leads in an approximately straight line therethrough, a driven actuator, devices rendered active by the fall of the controller arm for coupling the actuator to the stopping devices, and means rendered active by the movement of the movable guide under an increased tension on the thread for operating the cutter.

12. A stop-motion for knitting machines, having, in combination, stopping devices, mechanism for rendering the devices active to stop the machine when the continuity of the knitting thread is broken, comprising a thread guide having a substantially vertical face, guides above and below said guide for directing the thread therethrough in a substantially vertical line, and a pivoted controller arm extending horizontally from its pivot across the face of said guide between the thread and the face of the guide and supported by the thread.

13. A stop-motion for knitting machines, having, in combination, stopping devices, mechanism for rendering the devices active to stop the machine, comprising a knot arresting thread guide, shears above the guide, a thread guide above the shears having a substantially vertical face, a shear-control-

ling thread guide above the latter guide, a pivoted thread supported controller arm extending horizontally from its pivot across the face of the substantially vertical guide, 5 and means between the controller arm and stopping devices for operating the devices when the controller arm falls.

14. A stop-motion for knitting machines, having, in combination, stopping devices, a 10 rock shaft the movement of which renders the stopping devices active to stop the machine, a rotary actuator shaft carrying a star wheel, a pin on the rock shaft normally at one side of the star wheel, and a thread-controlled coupling pin for connecting the 15 star wheel and rock shaft.

15. A stop-motion for knitting machines, having, in combination, stopping devices, a 10 rock shaft, the movement of which renders the stopping devices active to stop the machine, an actuator shaft, a yarn guide having a substantially vertical face, a pivoted controller arm extending horizontally from its pivot across the face of the guide and 15

normally supported by the thread passing 25 therethrough, and devices for coupling the actuator and rock shafts which are controlled by the controller arm.

16. A stop motion for knitting machines, having, in combination, stopping devices, a 20 rock shaft the movement of which renders the stopping devices active to stop the machine, a rotary actuating shaft parallel to the rock shaft and carrying a star wheel, a radial pin on the rock shaft at one side of 35 the star wheel, a coupling pin for connecting the star wheel and radial pin, and a thread supported controller arm connected with the coupling pin for holding it out of engagement with the star wheel when supported by 40 the thread and for engaging it with the star wheel when released by a break in the continuity of the thread.

OLIVIER LAROCHE.
